UNITED STATES PATENT OFFICE.

CHARLES F. L. KAUFMANN AND WALLER L. KAUFMANN, OF SANTA ANA, CALIFORNIA.

CARBURETOR.

Application filed October 28, 1918. Serial No. 260,042.

This invention pertains to carburetors, more especially of the type employed with variable speed engines and an object of the invention is to produce a carburetor having maximum efficiency and one that is not liable to get out of order.

Other objects and advantages will appear in the subjoined detailed description.

The accompanying drawings illustrate the invention:

Figure 1 is an elevation mainly in vertical mid section of a carburetor built in accordance with the provisions of this invention.

Fig. 2 is an enlarged view mainly in section on line indicated by x^2-x^2 , Fig. 1.

Fig. 3 is an enlarged sectional elevation on line indicated by x^3-x^3 , Fig. 2.

Fig. 4 is a view analogous to Fig. 3 showing a modified construction of the needle valve for controlling the auxiliary fuel supply.

Fig. 5 is an enlarged sectional elevation on line indicated by x^5-x^5 , Fig. 2.

Fig. 6 is an enlarged fragmentary detail of the nozzle adjusting gage.

Fig. 7 is an enlarged fragmental sectional elevation of the nozzle portions of the carburetor.

Fig. 8 is a plan section on line indicated by x^8-x^8 , Fig. 7.

Fig. 9 is a plan section on line indicated by x^9-x^9 , Fig. 7.

Fig. 10 is a perspective view of the outer adjustable nozzle head in Fig. 7 and the fuel spreader, a portion of the fuel spreader being broken away to show the interior construction more clearly.

Fig. 11 is a perspective view of the inner adjustable nozzle head in Fig. 7.

There is provided a body comprising a tubular air passage 1 and an auxiliary air inlet passage 2 projecting laterally from the passage 1 and communicating therewith. At its outer end the air inlet passage 2 is provided with an air inlet port 3 controlled by a valve 4 adapted to seat on a valve seat 5. The valve 4 may be operated at will and for this purpose is provided with a valve stem 6 operated by any suitable mechanism indicated in general by the character 7, said mechanism not being shown and described in detail herein since such mechanisms are well understood in the art pertaining to carburetors.

The air passage 1 is provided with an ex-

ternal nozzle tube 8 which communicates at its lower end with a fuel chamber 9, the air passage and fuel chamber being separated from one another by a partition 10. Inside 60 of the external tube 8 is an internal nozzle tube 11 spaced from the external tube to form an annular nozzle fuel passage 12. The lower end of the internal nozzle tube 11 is provided with an annular flange 13 which forms the bottom of the fuel chamber 9 and which is screw-threaded into a main air passage 14.

In the instance shown in the drawings 70 the air passage 14 is constructed in sections and the upper section is integral with the fuel chamber 9 and the lower section is of U-shaped construction and is provided at its outer or intake end with a spherical head 15 having air inlet ports 16. The air passage 14 is controlled by a butterfly valve 17 operated by an arm 18 which is fastened to the shaft 19 of the butterfly valve. The arm 18 is pivoted at 20 to an operating rod 21 which may extend to within reach of the 80 operator so that he may readily adjust the butterfly valve 17. A hollow locking nut 22 is screw-threaded into the air passage 14 against the flange 13 so as to prevent turning of said flange.

The upper end of the internal tube 11 85 communicates with the air passage 1 and the lower end of said tube communicates through the nut 22 with the air passage 14 so that air drawn through the ports 16 passes through the air passage 14, thence through the nozzle tube 11 into the air passage 1.

The air passage 1 forms a mixing chamber for the air and fuel and the outlet 23 95 at the upper end of the air passage 1 is controlled by a butterfly valve 24 having a hub 25 which is fastened by a screw 26 or its equivalent to a tubular valve 27 formed by the inner end of a shaft 28 that extends 100 through the hub and that is operated by an arm 28', said shaft being journaled at its outer end in the air passage 1. The valve 27 and hub 25 are provided with a port 29 which is adapted to communicate, when the valve 24 is in closed position, with a port 29' extending transversely to the axis of a stud 30 that extends into the tubular valve 27 and that serves to journal the inner end 105 of the shaft 28. The outer end of the stud 30 forms a head 31 which may be fastened by a screw 32 or its equivalent to the outer

face of the air passage 1. The port 29' communicates with a fuel duct 33 in the stud 30. The outer portion of the fuel duct 33 is enlarged at 34 and the enlarged portion is provided with a needle valve 35 to regulate the amount of fuel flowing through the duct 33, the needle valve 35 being screw-threaded at 36 into the head 31 so that the needle valve may be adjusted by turning it. In Fig. 2 the needle valve 35 is screw-threaded into the head 31 axially of the stud 30 and is provided at its outer end with an arm 36' whereby the needle valve may be turned for adjusting it. In the modification shown in Fig. 4 the needle valve 35 is screw-threaded into the head 31 and is normal to the axis of the stud 30 and may be turned by any suitable means, not shown.

The fuel duct 33 communicates near its outer end with a fuel pipe 37 which in turn communicates with a float chamber 38. It may be desirable to have a hand-operated valve in the fuel pipe 37 and such a valve is indicated at 39. The float chamber 38 also communicates through a port 40 with the fuel chamber 9. It is clear from the foregoing that when the throttle valve 24 is in closed position fuel will be drawn from the float chamber 38 into the pipe 37 and thence through the duct 33 and ports 29, 28 to the air passage 1 above the throttle valve. The valve 39 may be operated by an arm 41 and said arm may in turn be operated by a rod 42 which extends to within easy reach of the operator. The throttle arm 36 may be operated by a rod 43 which may also extend to within reach of the operator.

The upper end of the external nozzle tube 8 is provided with an upwardly and outwardly beveled face 60 corresponding to an outwardly and upwardly beveled face 61 on an outer nozzle head 62 which is adjustably screw-threaded onto the upper end of the internal nozzle tube 11. The nozzle head 62 is provided with an upwardly and outwardly expanding funnel shaped outlet and fuel spreader 63. The adjustment of the nozzle head 62 is effected, in this instance, by reason of the nozzle head being screw-threaded onto the upper end of the internal nozzle tube 11. Thus turning of the nozzle head will move the head toward or from the upper end of the external nozzle tube 8 to change the cross sectional area of the nozzle orifice. Turning of the nozzle head 62 is effected, in the instance shown, by a bridge 47 connected to an adjusting rod 49 which extends vertically and axially of the internal nozzle tube 11 and through a portion of the air passage 14 and projects through the wall of the air passage 14. The projecting lower end of the rod 49 is provided with an arm 50 which is operated by a rod 51 that extends to within reach of the operator so that by operation of the rod 51

he may produce turning of the nozzle head 46 and consequent adjustment of said nozzle head relative to the external nozzle tube. A gage may be employed to indicate to the operator the size of the nozzle opening and for this purpose the projecting end of the rod 49 is provided with a flange 52 that may be marked on its periphery with graduations 53, any one of which may be brought into registration with an indicating mark 54 on a boss 55 which is formed on the outer face of the U-shaped portion of the air passage 14.

Inside of the internal nozzle tube 11 is a supplemental nozzle tube 64 having at its lower end a flange 65 which is screw-threaded into the internal nozzle tube 11, there being a hollow locking nut 66 also screw-threaded into the internal nozzle tube 11 against the flange 65 to prevent said flange from turning. The supplemental nozzle tube 64 is spaced from the inner nozzle tube 11 to form an annular passage 67 and said passage is separated by the flange 65, which forms a partition, from the lower portion of the interior of the inner nozzle tube 11. The inner nozzle tube 11 is provided with a port or ports 68 which afford communication between the fuel passages 12 and 67. The upper end of the supplemental nozzle tube 64 is upwardly and inwardly beveled at 69 to correspond with the upwardly and inwardly beveled face 70 of an inner adjustable nozzle head 71 which is screw-threaded into the internal nozzle tube 11 for adjustment purposes. The inner nozzle head 71 is provided with a bridge 72 which is connected by a tubular shaft 73 to an operating arm 74, said tubular shaft surrounding and being journaled on the shaft 49.

The operation of the elements of the carburetor thus far described is as follows: Assuming that the air passage 1 is connected in the usual manner to the manifold of an internal combustion engine, that fuel, as indicated at a, Fig. 1, is in the chambers 9 and 38, and that the valves 4 and 24 are closed, the engine will be started into operation by hand or power cranking in a manner well understood in the art pertaining to internal combustion engines so as to create a partial vacuum in the portion of the air passage 1 that is above the throttle valve 24. The throttle valve being closed the ports 29', 29 will be in register with one another and thus suction will occur in the pipe 37 so as to draw fuel from the float chamber 38 through said pipe into the air passage 1 above the throttle valve. The throttle valve does not fit so tightly in the air passage 1 but that there is a relatively small leakage of air past said valve and this air, together with the fuel sucked through the pipe 37, will produce a relatively rich mixture on

which the engine will easily start into self-operation in a manner well understood in the internal combustion engine art. The engine will operate at relatively low speed 5 on this mixture. When higher speed of the engine is desired the operator will open the throttle valve 24, for instance, to the position shown in Fig. 5 of the drawings, thus closing the port 29 whereupon suction produced by the engine no longer occurs in the pipe 37. This opening of the throttle valve causes the engine suction to be applied adjacent the fuel nozzle in such degree as to cause the fuel to be sprayed from the 10 nozzle orifice into the air passage 1. Air enters through the air passage 14 and passes through the internal nozzle tube 11 and spreader 63 into the air passage 1 where it mixes with the fuel from the nozzle. It is 15 noted that when the fuel nozzle is in operation to spray the fuel, whatever fuel is not immediately absorbed and carried away by the air is sprayed outward against the inner face of the spreaders 63. The valves 4 and 20 17 will be adjusted according to the relative amounts of fuel and air desired in the mixture, as is readily understood. Thus whatever fuel is sprayed from the nozzle in excess of that immediately taken up by the air, 25 is spread upon the inner face of the spreader 63 and is taken up by friction of the air as it passes therethrough.

To change the ratio of fuel to air regardless of the degree of opening of the valves 30 4 and 17, the operator will turn the operating arm 50 in one direction or the other to increase or diminish the cross sectional area of the nozzle orifice formed by the space between the beveled faces 60 and 61. Also 35 40 the operator may change the proportion of fuel to air regardless of the degree of opening of the valves 4 and 17 by operating the arm 74 so as to move the beveled faces 69, 70 toward or from one another as the case 45 may be to increase or diminish the cross sectional area of the inner nozzle orifice.

The construction of the float chamber 38 and its parts will now be described in detail, provision being made to adjust to a high 50 degree of precision the level of the fuel *a*. In the float chamber 38 is a float 75 through the vertical axis of which extends a needle valve 76 controlling the flow of fuel through a fuel duct 77 in a stem 78 that is screw-threaded into a hollow boss 79 projecting downward from the bottom of the float chamber 38. Surrounding the lower end of the needle valve 76 and the boss 79 is a chamber 80 which is provided with a packing gland 81 for the stem 78. The upper 55 end of the needle valve 76 passes through and is guided by a hollow boss 82 and projects above said boss. The boss 82 is screw-threaded to receive a cap 83 which thus

makes a tight closure over the upper end of 65 the needle valve 76. The chamber 80 is supplied with fuel through a fuel pipe 84 which may be connected to a fuel tank, not shown. The needle valve 76 is provided with a collar 85 and pivoted to said collar 70 are levers 86 which in turn are pivoted at 87 to brackets 88 projecting downward from the top of the float chamber 38. The outer ends of the levers 86 are engaged by the upper end of the float 75 and the up and down 75 movement of the float 75 will thus move the needle valve 76 downward and upward to regulate the flow of fuel from the fuel chamber 80 to the float chamber 38 in a manner easily understood to determine the level to 80 which the fuel *a* will rise in the carburetor.

The level to which the fuel may rise and at which it is maintained is predetermined by the level of the valve seat 89 relative to the level of the float when the levers 86 engage said float. To raise the fuel level the stem 78 will be turned to screw it outward or downward and to lower the fuel level the stem 78 will be turned to screw it inward or upward. 90

The invention is not limited in its broader phases to the exact details of construction shown in the drawings and above described and it is understood that the invention also includes such changes and modifications as 95 lie within the spirit and scope of the appended claims.

We claim:

1. In a carburetor, three stationary concentric nozzle tubes forming intermediate 100 fuel passages, the inner tube forming an air passage of fixed area, annular heads carried by the middle tube axially adjustable thereon and cooperating with the upper ends of the inner and outer tubes respectively to 105 form an annular fuel discharge orifice for each fuel passage, said adjustable heads having concentric air passages of fixed area, means for adjusting the heads to vary the sizes of the orifices, and means to supply 110 fuel to the spaces between the tubes.

2. In a carburetor, three concentric nozzle tubes forming intermediate fuel passages, the inner tube forming an air passage of fixed area, annular heads carried by the middle tube, and axially adjustable thereon and cooperating with the ends of the inner and outer tubes respectively to form an annular fuel discharge orifice for each fuel 115 passage, said adjustable heads having concentric air passages of fixed areas, means for adjusting the heads to vary the size of the orifices, and means to supply fuel to the spaces between the tubes. 120

Signed at Los Angeles, California, this 125 17th day of October, 1918.

CHARLES F. L. KAUFMANN.
WALLER L. KAUFMANN.
